JEARUM ATKINS, OF WASHINGTON, DISTRICT OF COLUMBIA.

Letters Patent No. 85,779, dated January 12, 1869.

IMPROVEMENT IN GOVERNORS FOR MARINE AND OTHER ENGINERY.

The Schedule referred to in these Letters Patent and making part of the same.

To all whom it may concern:

Be it known that I, JEARUM ATKINS, of Washington, District of Columbia, have invented new and useful Improvements in Governors for Marine Engines and other Motors; and I hereby declare the following to be a full and exact description thereof, reference being had to the drawings which accompany and form a part of these specifications.

The propelling-wheels of steam-vessels, in heavy weather, are often thrown almost instantaneously, either partly or entirely out of water, thereby relieving the engine suddenly of almost its entire load, when a fearful increase in its speed takes place, unless some adequate power is brought into play in time to check the supply of steam. Nor is it less important that the full supply of steam should be again admitted to the engine so soon as the emergency is passed, and the wheel finds itself again submerged. Therefore, a governor, in order to be efficient in controlling the speed of the engines of large ships, is required to possess the following qualities: first, extreme sensitiveness; second, great power to move instantaneously the ponderous throttle-valves or other devices used for regulating the admission of steam to the engine; third, freedom from being disturbed in its action by the motion of the ship.

Many marine-engine governors have been devised, although none, it is believed, have been found capable of fulfilling all of the above conditions.

The form of governor which has been generally adopted for this purpose is that known as the centrifugal governor, having revolving weights, in which the centrifugal force of said weights has, in some cases, been counterbalanced by their own gravitation, and, in other cases, by means of springs, so arranged as to be compressed when the revolving weights recede from their axis of motion, owing to increasing centrifugal force due to any acceleration of motion in the engine, and *vice versa*. The power of these springs must bear such a relation to the centrifugal force of the revolving weights, that when the engine is working at its proper speed the two forces will exactly balance each other, and no change of position in the revolving weights will take place while the engine maintains its uniform speed. The only cause of the revolving weights changing their position, in consequence of changes in the speed of the engine, lies in the fact that while the elasticity of the spring is a constant quantity, (so long as its form remains unchanged,) the power of centrifugal force to overcome said elasticity changes with every variation in the speed of the engine, the quantity of centrifugal force being as the square of the number of revolutions performed by the weights in a given time, while the diameter of their circle of rotation remains constant; and when their circle of rotation is allowed to change, it is as the square of the number of revolutions in a given time, multiplied into the diameter of said circle of rotation.

The only effective power of a governor of this class which is available in controlling an engine, is the excess of centrifugal force which is due to any increase of motion above the elastic force of the spring, in case of accelerated motion of the engine, and the diminution of centrifugal force below the elastic force of the springs, in case of the motion of the engine being retarded.

A considerable portion of even this small amount of power is neutralized, in consequence of the elastic force of the spring increasing and diminishing as the centrifugal force of the weights increases and diminishes; hence it follows that only a small amount of power is obtained, which is altogether inadequate to operate the throttle-valves of large engines by the use of a governor, the proportions of which are within practical limits.

A governor of such enormous size as would be required to furnish power sufficient to control the largest class of engines, would be so unwieldy and sluggish in its action, as to be wholly inadequate to perform this office.

My invention relates to a governor which is designed to fulfil all the before-named conditions; and

It consists—

First, in constructing a governing-device of very small dimensions, and in rotating the same at a very high speed, so as to secure high centrifugal force with very slight inertia, and a capacity for very rapid change in the rate of movement.

Second, in arranging the parts of said governing-device so that its centrifugal weights shall move always in a plane perpendicular to their axis of motion.

Third, in arranging a counterpoise to balance the weight of the moving parts of the primary governor.

Fourth, in arranging said primary governor to control the flow of a fluid under pressure, so that said fluid shall act upon a piston to move the throttle-valve, in accordance with the movements of said governing-device, producing an apparatus which serves, as it were, to give the word of command, or as a leader for controlling the pressure of a fluid, which fluid is caused to act upon a piston working in a cylinder, the action of said piston being employed to move the throttle-valve of the engine to be governed, the arrangement of all the parts being such that the said actuating-piston is controlled by and moves in accordance with the said primary governing-device, as hereinafter explained.

Figure 1 is an elevation of the governor and its attachments; that portion contained between the horizontal lines A B being in section, to show the internal construction.

Figure 2 is a horizontal section, half size, on line C on fig. 1.

Figure 3 is a horizontal section, half size, on line B on fig. 1.

Figure 4 is a horizontal section, in part, on line D on fig. 1.

Figure 5 is a horizontal section, in part, on line E on fig. 1.

Figure 6 is a vertical section of the connecting-rod F, fig. 1.

Figure 7 is an elevation of the upper portion of the governor, taken at right angles with that shown in fig. 1.

Figure 8 is an enlarged view of a portion of one of the weighted levers and its immediate connections.

Figures 9, 10, 11, 12, and 13, sheet 2, are enlarged views of several of the figures shown on sheet 1.

Figure 14 is a perspective view of my apparatus complete.

The same letters refer to like parts in all of the several figures.

A short cylinder, G, of large diameter, having a square base, serves as a foundation for the four columns, H, which support the smaller jacketed cylinder I, and upon this cylinder I is raised the pedestal J of the centrifugal governor. This pedestal J is hollow, and contains within it the hollow spindle K, and within this spindle K is contained the smaller solid spindle L, shown in dotted lines.

To the top of the spindle L is attached the slide M, to which the weighted levers N are jointed, and to the middle points of these levers are jointed the levers O, which have their centres of motion in the short cross-head P, fixed to the revolving spindle K.

The slide M is guided vertically in a large mortise in spindle K, in which it moves freely up and down, as the circle in which the centres of the centrifugal weights Q revolve enlarges and contracts, owing to variations in the speed of the engine.

A spring, R placed between the upper ends of the levers N, serves to counteract the centrifugal force of the weights Q, in place of gravitation, which, owing to the peculiar construction, has no part to play in the working of the governor, and does not act, in any degree, as a disturbing-force when the ship rolls, or is lifted up and down by the force of the waves.

The joints by which the levers N are suspended to the slide M, and the joints connecting the levers O with the spindle K, are on the same vertical lines, and the length of the levers O being one-half that of levers N, the former being jointed to the latter at their middle point, (reckoning from the centres of the weights to the joints by which they are suspended to the slide M,) it follows that the centres of the weights will traverse a perfectly horizontal plane in moving to and from their axis of rotation; and it follows, also, that (as before stated) the effect of gravitation is thereby entirely got rid of, and does not act as a disturbing-force when the position of the governor is changed.

When the revolving weights of a governor move away from their axis of rotation in a curved line, a portion of the centrifugal force due to any acceleration of motion, is absorbed in overcoming the gravity of said weights; for, while they recede from their axis of rotation, they are also raised to a higher plane, the increase of radius being indirect, and only equal to the elongation of the chord due to the elongation of the arc described by the weight in moving. This absorption of power does not take place when the weights recede from their axis of rotation in a straight line, for in that case every increase of motion is a direct increase of radius, and it follows that a certain increase of radius, and its corresponding increase of centrifugal force, will be attained with a less application of power.

Fig. 8 represents the pins S, for connecting the levers N with the slide M, V-shaped or knife-edged, to avoid friction, thereby increasing the sensitiveness of the governor.

The small central spindle L serves to communicate motion from slide M to a lever, T, which is poised upon the small pedestal U, the usual grooved collar and

clutch being employed to connect the former with the latter.

Figs. 12 and 13 represent the manner in which the spring R is held in its place between the hooks at the ends of the levers N, which is by placing on the ends of the spring flat rings, V, one of which is seen edge-wise in fig. 13, and flatwise in fig. 12, a V-shaped cavity being formed in each, to receive the points of the hooks on levers N.

Motion being communicated, by suitable gearing, from the engine or other motor to be governed, to the spindle K, the lever T will vibrate in accordance with any changes in the speed of the motor.

This completes the description of the centrifugal governor, except in relation to its power to maintain a uniform speed in the motor to be governed, which will be treated upon hereinafter.

The connecting-rod O' is formed of two pieces, joined together at the centre by means of a reversible nut, F', into which both halves of said rod are screwed, one half having a right, and the other a left-hand screw. By turning this nut in opposite directions, the connecting-rod may be either lengthened or shortened, at pleasure, by which means the governor may be adjusted for changing the speed of the engine, whenever desirable, as will be more fully explained further on.

This nut F' serves also to counterbalance the slide M', spindle L', and its attachments, and prevent the weight of those parts from creating any disturbance in the action of the governor.

The cylinder I has fitted to it a piston, Q', whose piston-rod, R', is connected with and communicates any motion of said piston to the throttle-valve of the engine. This piston-rod has two longitudinal passages, S T, passage S leading to the bottom, and passage T to the top of the cylinder.

A horizontal arm, U', fixed to the piston-rod, contains also two longitudinal passages, V W, passage V communicating with passage T, and passage W with passage S in the piston-rod.

The arm U' has fitted into it the cylindrical slide-valve casing X, within which is the cylindrical slide-valve Y, which controls the ports Z Z', opening into the passages V and W, which extend entirely around the valve-casing X, as represented in fig. 4.

The spindle J' of the slide-valve Y being connected, through lever K', rock-shaft L', lever M', connecting-rod O', and the before-named lever T and spindle L and slide M, with the weighted levers of the centrifugal governor, any motion in said weighted levers, caused by the expanding or contracting of the circle of rotation of the revolving weights, will be communicated to the slide-valve Y.

Supposing, now, that some fluid, as air, steam, or water, under pressure, is introduced into the slide-valve casing X, through the induction-pipe Q", and suppose that by an acceleration of the speed of the engine, and consequent enlargement of the circle of rotation of the revolving weights, the slide-valve y is suddenly elevated, (in which action lever M' will be thrown into an inclined position, as shown at M", in dotted lines,) and all the ports Z Z', &c., will be uncovered. The propelling-fluid will now enter the bottom of the cylinder through the ports Z Z' and passages W S, and force up the piston; and as the piston rises, it carries along with it the valve-casing X, (and all its attachments,) until the lever M is again brought to a horizontal position, (or to the dotted line M"), and the valve y again covers all the ports Z and Z', shutting off the fluid-pressure from the piston, and no further motion of said piston can take place until some further change takes place in the position of the revolving weights.

It will be understood that when the circle of rotation of the revolving weights contracts, the slide-valve y will be moved down again, uncovering all the ports Z Z',

&c., and that an action, the reverse of that last described, will take place, the propelling-fluid entering the top of the cylinder through the ports Z Z, passages V and T, and forcing the piston down, while the fluid that lifted it up escapes through the same passages by which it entered, to the slide-valve casing, and thence through the exhaust-ports I and exhaust-pipe H'.

It will also be understood that the piston will always move exactly in accordance with the connecting-rod O', invariably moving just as far as and no further than the connecting-rod, because, when it has done so, the ports admitting the propelling-fluid to the cylinder, and allowing it to escape therefrom, are all closed, and hence it is plain that the piston can settle at no other point than that at which it is arrived when the lever M' occupies a horizontal position.

From the above description it will be perceived that while the action of the primary governing-device moves the valve Y to open the ports Z Z, the movement of the piston causes those ports to close again; and if, from the effect of momentum or other cause, the piston should move further than the point of equilibrium, the exhaust-port will thereby be uncovered, and the other induction-port also, so that at the moment of passing the point of equilibrium, the propelling-force will be permitted to exhaust, and a resisting-force will be introduced at the other side of the piston. It is, therefore, plain that no excess of movement of the piston can possibly take place.

Now, by connecting the piston-rod R' (in any convenient manner) with the throttle-valve or other "cut-off" device of a steam-engine or other motor, the governor will have just the same action upon said throttle-valve or cut-off as though the lever T had been connected directly with it, in the usual manner, except in this, that while the centrifugal governor exerts only a small amount of power to move the lever T, which may be only sufficient to move the light device, which controls the slide-valve y, the piston-rod R' will exert an amount of power, the expression of which is found by multiplying the area of the piston Q' by the pressure of the fluid by which it is actuated.

To the bottom of the piston-rod R', which extends down into the cylinder G, containing a fluid, is fixed a piston, A', which has two openings, B B', (see fig. 2,) through it.

These openings are either partially or entirely closed, at pleasure, by means of the adjustable cover C', fixed to the bottom of the short tube D', which fits loosely over the piston-rod R'.

This tube D' extends up through the cylinder-cover, and has fixed to it the index E', by which the cover C' may be adjusted, so as to close such a portion of the openings B B' as may be desirable, and by which the portion of said openings so covered is indicated upon a graduated scale marked upon the cylinder-head. A nut, F', screwed upon the piston-rod, is for clamping the cover C' in any position.

The office of the piston A', which is immersed in the fluid contained in the cylinder G, is to counteract any vibrations or irregularities in the motion of piston Q', which might take place in consequence of using an elastic fluid as a motive-power.

In case of using hydraulic pressure to operate the governor, this last-described device may be dispensed with.

The devices, which serve to communicate motion from the centrifugal governor to the slide-valve y, may be somewhat simplified by extending the valve-spindle J' up through the top of the valve-casing, and connecting it directly with the lever T, as shown in dotted lines in fig. 1, the objection to this latter mode being that packing would be required to secure a tight joint between the spindle J' and the valve-casing.

This last-named mode would not be objectionable, however, when atmospheric pressure is used to operate

the governor, as in that case the slide-valve casing might be left open at top and bottom to the surrounding air.

In applying this governor to regulate non-condensing engines, the induction-pipe Q" should be connected with the boiler, or otherwise with the steam-pipe which supplies the engine, and the exhaust-pipe H' should connect with the exhaust-pipe of the engine.

Both the induction-pipe Q" and exhaust-pipe H' require to be flexible, to allow the valve-casing, to which they are attached, to rise and fall with the governor-piston.

In applying it to regulate condensing-engines, steam may be used as in case of applying it to non-condensing-engines, although it is believed that a better move would be to use atmospheric pressure as the motive-power, which may be done by simply leaving the valve-casing X open at top and bottom to the surrounding atmosphere, and connecting the exhaust-pipe with the condenser of the engine. In this manner the atmospheric pressure may be made available, amounting, in ordinary cases, to about fourteen pounds to the square inch.

In this application, the corrosive effects of steam, and liability to condensation in the cylinder, are all obviated.

Still another mode of operating this governor is by hydraulic pressure, to effect which it is only necessary to connect the induction-pipe Q" with the water-supply pipe of the boiler, and let the exhaust-pipe carry off the waste water.

In using hydraulic pressure as the motive-power, as above, it might be found necessary to increase the area of the ports and passages for supplying the water to the piston Q', as the velocity with which this fluid moves through pipes, under a given pressure, is much less than that of steam or air, owing to its superior density.

In order to adapt this governor more perfectly for the use of steam as the motive-power, I enclose the cylinder I in an outside cylinder or jacket, between which and said inside cylinder live steam is introduced through the pipe d, for maintaining a high temperature, and preventing condensation in the inside cylinder, lest the water, which might otherwise be formed thereby, should impede the action of the piston, and thus disturb the operation of the governor.

The pedestal J, with its broad base standing on the top of the cylinder I, might become too highly heated, and, together with the mechanism connected with it, be injuriously affected thereby, in case of using steam as the motive-power; but in order to prevent such a result, I introduce some non-conductor, as plaster of Paris or charcoal, into the space e, between the head of the cylinder I and the base of the pedestal, by which a high temperature in all the parts above said non-conductor is prevented.

The connection between the piston-rod R' and the throttle-valve must be such that when the centrifugal weights are collapsed, and the piston Q' at the bottom of the cylinder I, as represented in the drawings, the throttle-valve will be open.

Now, should the connecting-rod O' be shortened, by turning the reversible nut F, (as already explained,) the lever M' will be thrown into an inclined position, by which the slide-valve y will be elevated, and the propelling-fluid admitted to raise the piston (as before shown) an amount equal to the shortening of the rod O', by which the throttle-valve will be partially closed without any change in the circle of rotation of the revolving weights.

It will thus be understood that shortening the connecting-rod O' reduces the speed of the engine, and vice versa.

Fig. 14, sheet 2, represents a four-way cock, which is designed to be used in place of the slide-valve y, al-

ready described, by which the slide-valve casing X may be dispensed with, and the mechanism used to control the action of the propelling-fluid upon the piston, otherwise considerably simplified.

The plug A'' of the four-way cock works in a casing, U', which corresponds to the arm U, as before described, and is fixed in the same manner to the piston-rod R'.

This casing U' has the same or similar passages, V' W', communicating with the passages T S in the piston-rod.

It has also a similar induction-pipe, Q'', and exhaust-pipe H', connected with it, and for the same purpose as before described.

A portion only of the piston-rod R' and connecting-rod O' is shown in the drawings.

Now suppose, as before, that the connecting-rod O' is drawn up by an increase in the diameter of the circle of rotation of the centrifugal weights, until the lever M', which is fixed to the back end of the four-way cock, assumes the inclined position represented in dotted lines at M''.

By this action, the plug of the cock will be turned round, as shown in dotted lines, and all the passages leading from the induction-pipe Q'' to the bottom of the cylinder will be open, as also all those leading from the top of the piston to the exhaust-pipe H'. The propelling-fluid will now rush into the bottom of the cylinder, and force up the piston, while the contents of the upper portion of the cylinder escape through the passages T V', the four-way cock, and the exhaust-pipe H'.

The piston will rise, as before explained, carrying the four-way cock up with it, until the lever M' is again horizontal, as shown at the horizontal line M'', when the cock will assume its original position, closing all the passages leading to the cylinder, by which the piston will be locked in its place so long as the connecting-rod O' is stationary.

It is needless to remark that when the connecting-rod O' descends, an action the reverse of that described takes place, and that, in all cases, the piston follows the motion of the connecting-rod O', whether the four-way cock or slide-valve is used to control the ports by which the propelling-fluid is admitted to act on the piston Q'.

It is not supposed to be possible to construct a governor that will maintain a perfectly uniform speed in a marine engine, when the ship is laboring in a heavy sea, nor is it necessary that a governor should be capable of effecting such a result. All that is aimed at in this invention, so far as it relates to marine engines, is to soften down and ease off the violent shocks caused by the sudden changes in the resistance which the wheels meet, unless some means are resorted to for regulating the admission of steam in accordance with the amount of such resistance.

The above is not true, however, in regard to engines for propelling the machinery used in cotton and woolen-factories, flouring-mills, &c., in which the degree of perfection with which the work is performed depends in a great degree upon the uniformity in the speed of the machinery.

In adapting this governor in the most perfect manner for regulating the latter class of engines, advantage is taken of the well-known laws of elasticity and centrifugal force, upon which much stress was laid, in the first part of this specification, viz, that the centrifugal force of bodies revolving in a circle increases and diminishes in a direct ratio to the diameter of their circle of rotation, while the number of revolutions performed in a given time remains constant, and that the elastic force of springs increases as the ratio of the space through which they are deflected.

Now, suppose the centres of the weights Q to be made to coincide with their axis of rotation, and lines to be drawn through the latter point, and extended

through the centres of the joints by which the levers N are attached to slide M, to the point of contact of said levers with the spring R; and suppose the length of the levers N, from their points of suspension to the centres of weights Q, to be four inches, and to the points of contact with spring R, one inch, then their leverage will be as four to one. Let the spring R be of such proportions that it will open out to the points at which lines c' intersect lines d', when not bent out of its natural form.

The centrifugal force of the weights while their centres coincide with their axis of rotation will be nothing, and the spring is not supposed to exert any pressure against levers N until said levers change their position in respect to their axis of rotation.

Now, suppose the weights Q to open out one inch, or to revolve in a circle of two inches in diameter, and let the velocity with which said weights revolve be such that the centrifugal force generated in each will be one pound. The spring will, by this change of position in levers N, be deflected one-quarter of an inch, and its stiffness must be such that when so deflected, it will exert a pressure on levers N of four pounds, in order to balance the centrifugal force of the weights. Now, let the circle of rotation of the weights be increased to four inches, (each moving out one inch, as before,) the centrifugal force of each weight will now be increased to two pounds, and the elastic force of the spring, in order to balance it, must, by being thus deflected another quarter of an inch, be increased to eight pounds. And we find this is actually the effect of said deflection, by the law that elastic force increases in a direct ratio with the amount of deflection.

From the foregoing, it is plain that when the elastic force of the springs is such that it will balance the centrifugal force of the weights in one position, it will do so when they occupy any other position in respect to their axis of motion, allowing all the above-named conditions in relation to construction to be complied with; but these results will not follow if the points of contact between the levers N and spring R are not upon lines which cut through the axes of motion between said lever and the collar M, and through the centres of gravity of the weights Q.

Hence, it follows, that no change in the speed at which the governor revolves will be required to cause it to open and close the throttle-valve, for regulating the quantity of steam to be admitted to the engine, according to the resistance against which it is working, except only the small amount which is required to overcome the friction of the moving-parts, and that the governor, considered theoretically, would be capable of maintaining a perfectly uniform rate of motion in the engine without regard to the amount of power developed.

When this governor is designed for regulating marine engines, the spring should be so proportioned that it will not meet the points of levers N until the weights Q have receded some distance from their axis of motion, in which case a certain increase in the velocity of the engine will give the spring a certain degree of deflection, and a further increase in the speed of the engine, a still greater degree of deflection, and so on.

It should be further observed that the spring should possess greater stiffness, to adapt the governor for regulating the latter class of engines, than would be required when it is designed to regulate the motive-power of manufacturing-establishments.

I am aware that the centrifugal weights of governors have been made to revolve in a single plane, perpendicular to their axis of rotation, but in most of those cases said weights are required to slide upon arms fixed to and at right angles with the revolving spindle. They are, therefore, necessarily obliged to overcome the amount of friction due to the specific gravity of the weights. My centrifugal weights move

freely upon knife-edges, if necessary, and are in no degree retarded by friction.

I am also aware that centrifugal governors have been made, the weights of which counterbalance the weight of the moving arms and their direct attachments. But in order to accomplish this, the said weights are required to move to and from the axis of rotation in a curved line. I consider it more advantageous to counterbalance the corresponding parts of my governor independent of the centrifugal weights.

I am further aware of the governor patented in England, by Wood, Whitehead, and Tetlow, in 1863. In that invention the throttle-valve receives its initial movement directly from the centrifugal action of the revolving weights, and said valve depends directly upon the sustaining-power of the centrifugal force of said weights for its continued movement. The revolving weights must, therefore, be large and powerful, and not quick and sensitive.

In my governor, the centrifugal force of the revolving weights does not act upon the throttle-valve directly at all, but only controls the flow of the fluid under pressure by which said valve is moved.

I do not claim anything embraced in the principles of action represented in the above-named cases.

Having thus described my invention, I desire to state, in conclusion, that I do not limit myself to the precise construction of parts herein described, as these may be almost infinitely varied, and still be capable of producing the same or similar results.

What I claim, and desire to secure by Letters Patent, is—

1. The piston Q', moved by a fluid under pressure, to control the throttle or other cut-off mechanism, in combination with the herein-described primary governing-device, constructed substantially as set forth.

2. In combination with the cylinder and piston, the latter of which is connected with and controls the throttle-valve or other cut-off mechanism, the valve and valve-seat, the latter of which is carried along with said piston, said valve connected with and operated by a primary governing-device, and said valve-seat having suitable ports and passages for the admission and emission, to and from either end of said cylinder, of the compressed fluid which moves said piston, substantially as herein set forth.

3. The valve Y, connected with and moved by the primary governing-device, to open the ports of admission and emission, in combination with the movable valve-seat connected with and moved by the piston Q', to close said ports, whereby the ports of admission and emission are opened and closed by the alternate movements of the valve and valve-seat, substantially as herein set forth.

4. The combination of the valve Y and the horizontal arm U with the cylinder I, as herein described.

5. The combination, with the hollow piston-rod R', valve Y, and its movable seat, of the hollow arm U', which is carried along with the piston, having the passages V W to communicate with the passages T S in said piston-rod, substantially as specified.

6. The arrangement of the slide-valve Y and valve-spindle J' with the lever M', rock-shaft L', lever K', and adjustable connecting-rod O', substantially as set forth.

7. The levers N, as constructed and arranged, whereby the points of contact with the spring R shall be on lines, or nearly so, which pass through the centres of the revolving weights, and through the axes of the joints which connect said levers to the slide M, as herein set forth.

8. The arrangement of the levers N with reference to the spring R, which is carried between and acts upon said levers equally, in opposite directions, substantially as specified.

9. The spindle K, constructed with a slot or opening for a guide-way for the slide M, substantially as set forth.

10. The construction of the cylinder-head e and the pedestal J, whereby an open space is formed to receive a non-conducting medium, substantially as set forth.

11. The levers N, braces O, and weights Q, constructed so that said weights shall always move in a horizontal plane, in combination with the counterpoise F, substantially as set forth.

12. In combination with the piston A', the adjustable cover C', tube D', index E', and clamping-nut F', substantially as set forth.

JEARUM ATKINS.
